(57) **CLAIM**

The ornamental design for a hydrogen energy folding bicycle, as shown and described.

DESCRIPTION

1. Hydrogen energy folding bicycle

1.1 is a front and right side perspective view of an hydrogen energy folding bicycle embodying our new design;

1.2 is a front elevation view thereof;

1.3 is a rear elevation view thereof;

1.4 is a top plan view thereof;

1.5 is a bottom plan view thereof;

1.6 is a right side elevation view thereof; and

1.7 is a left side elevation view.
